UNITED STATES PATENT OFFICE.

PAUL MAUSER, OF OBERNDORF-ON-THE-NECKAR, GERMANY.

MAGAZINE ARRANGEMENT FOR FIREARMS, ESPECIALLY FOR RECOIL-LOADING FIREARMS.

No. 922,497.

Specification of Letters Patent.

Patented May 25, 1909.

Application filed March 5, 1909. Serial No. 481,315.

To all whom it may concern:

Be it known that I, PAUL MAUSER, privy councilor of commerce, a subject of the King of Würtemberg, residing at Oberndorf - on-the-Neckar, in the Kingdom of Würtemberg, Germany, have invented certain new and useful Improvements Relating to Magazine Arrangements for Firearms, Especially for Recoil-Loading Firearms, of which the following is a full, clear, and exact description.

The present invention relates to fire arms, especially to recoil loading fire-arms, and the object of the invention, on the one hand, is to effect reliable guidance of the cartridge to its correct position, and on the other hand, rapid extraction and insertion of the same. With regard to the first purpose, namely, guiding the cartridge to the correct position, an arresting mechanism is provided in the magazine in combination with the cartridge elevator in order to prevent the rear part of the cartridge from tipping back, that is to say, to hold the cartridge elevator itself in the correct feeding position and to prevent it from tipping backward when the weapon recoils. This arrangement of the arresting mechanism necessitates an auxiliary device to release it when the magazine is being filled, in order that the cartridge elevator can be moved downward without its arresting pawl falling into the slots or cavities in the rear wall of the magazine. This new arrangement of the magazine with the previously described magazine arrester, also necessitates a new kind of magazine holder, which will prevent the magazine from being accidentally released by the recoil action or by any unusual strains of the weapon (such as shocks, blows and the like) by only allowing the holding parts to be released by an action or operation applied transversely to the longitudinal direction of the weapon, that is to say, at the side of latter.

In the accompanying drawing the new magazine arrangement is shown applied to a recoil-loading pistol.

Figure 1 shows the pistol with the magazine in longitudinal section and wherein the cartridge elevator is about to place the last cartridge in the course of the advancing breech bolt. Fig. 2 is a side view and rear view of the elevator plate with its guide slide and cylindrical projection for guiding the spring. Fig. 3 is a side and rear view of the magazine base plate. Figs. 4 and 5 show the

two positions of the magazine holder, namely, in the position of engagement and that of release. Fig. 6 is a front, side and rear view of the magazine holder locking lever. Fig. 7 is a side and rear view of the spring arm for actuating the holding locking lever. Figs. 8 and 9 show the device, use and action of the auxiliary mechanism for disengaging the arrester of the cartridge elevating platform when the magazine is being filled. Figs. 10, 11 and 12 are three different views of this auxiliary mechanism above *i. e.* dismounted.

The magazine *m* of the weapon is of the usual type arranged to be pushed in and pulled out of the stock and consists of a sheet metal casing containing the cartridge elevating platform and spring *p*^o and conforms in shape to the downward slanting position of the cartridges arranged one above the other. In this magazine, as clearly shown in Fig. 8, the cartridges are mounted one above the other in a slanting position, in such a manner that the uppermost cartridge *P* to be pushed by the breech bolt into the barrel is lifted by the cartridge elevating platform, after the return of the breech bolt, direct into the inserting position.

As already mentioned in the introduction, an arrester is arranged in conjunction with the cartridge elevator in order to prevent the rear part of the cartridge from tipping downward during the recoil, or in other words, to hold the cartridge elevator itself in the correct elevating position and prevent it from tipping backward during the recoil. It has been found in use that the recoil, by causing the weapon to be jerked up more or less, has resulted in the cartridges being thrown downward in the magazine; in order to prevent this the arrester is so arranged that the cartridge elevator and the whole row of cartridges thereon is held fast and secured against rearward or downward motion as each cartridge is placed in position step by step. With this end in view, in accordance with the invention, a spring arresting pawl *p*³ is fixed to the cartridge elevator, slots *m'* being provided in the rear wall of the magazine for said pawl *p*³ to engage with the step by step elevating position of the row of cartridges or of the cartridge elevator.

In order to keep the rear wall of the magazine sufficiently strong and to provide a symmetrical support two slots *m'* are preferably furnished for each step, as shown in Figs. 8

and 9, so that there are two rows or series of slots located as close to the edges of the wall as possible in order that there should be sufficient material in the center. With this arrangement the spring arresting pawl is correspondingly provided at its lower end, which engages with the slots, with two simultaneously engaging noses or tongues p^{3x} . As regards the cartridge elevator itself the elevator platform is provided with lateral wings to insure good guidance, and by means of which a guide slide is formed. The rear lower side of the cartridge elevator is further provided with a downwardly projecting cylindrical projection p' which serves as a guide for the cartridge elevator spring p^0 . The bottom of the magazine is closed by a base plate m^0 which is held in the closed position by means of lateral spring arms m^3 engaging with corresponding grooves m^{3x} in the side walls of the magazine. This base plate carries a block which slants upward at its rear end in such manner that it forms a base vertical to the direction of pressure of the cartridge elevator spring. After releasing a fastening pin m^x the base plate can be removed, for which purpose naturally the spring arms m^3 would also require to be released from the sides of the magazine. It should be further mentioned that, as regards the cartridge elevator and the arrester, the spring arresting pawl p^3 is preferably formed integral with the stop p^2 , which is adapted to hold the breech bolt open when the magazine is empty, and that this piece is secured by being inserted in grooves on the top of the cartridge elevator. The arresting pawl is, as previously mentioned, resilient; it might, however, be capable of a rocking or other movement and be actuated by a special spring. The arrangement of longitudinal slots m^2 in the sides of the magazine insures an exact guidance for the cartridge elevator spring fitting in said slots. In order to be able to fill the magazine, it is necessary, with regard to the arrangement of the arresting mechanism which prevents the cartridge elevator from being pushed down, to provide a special auxiliary device the construction and operation of which is shown in Figs. 8 to 12. This auxiliary device consists of a double or U shaped bent plate p^4 having on its narrow side downward slanting teeth or projections p^5 corresponding with the slots m' . This plate p^4 is fixed with its narrow side to the rear of the magazine (Figs. 8 and 9), so that the teeth or projections p^5 project into the slots m' and by thus closing these slots, prevent the noses or tongues p^{3x} of the spring pawl p^3 engaging with the said slots. Thus the cartridge elevator can be pressed down against the pressure of its spring and the cartridges P fed from above through the mouth of the magazine. When the cartridge elevator is pressed down, the arresting

pawl slides down inoperatively, i. e., over the teeth or projections p^5 without falling into the slots m' , as clearly shown in Fig. 8; the position of the parts being apparent with five cartridges in the magazine.

70

In order that the auxiliary tool should be capable of being readily fitted in position and securely held, the lowest tooth or projection p^6 has a hook shaped projection which is adapted to project through its corresponding slot and to grip the inside of the rear wall of the magazine. A handle p^x is preferably used for pressing down the cartridge elevator, this handle being inserted from the side through the corresponding slot m^2 into a hole p^7 provided for this purpose in the cartridge elevator. After having filled the magazine both tools, namely, the plate p^4 and handle p^x , can be removed, whereupon the magazine is ready for use and can be pushed into the stock. When in position in the stock the magazine is held by a magazine holder which is of such a construction that its release necessitates a lateral action, in order to prevent it from being inadvertently released by the recoil or other power acting in the longitudinal direction of the weapon. The construction and action of this magazine holder is clearly shown in Figs. 4 and 6. The holder, as shown, consists essentially of a locking lever n^0 pivoted to the rear of the magazine, which lever has on its forward side a shoulder n^x which engages underneath a projection m^4 on the rear of the magazine. This projection m^4 is preferably formed on the previously described slanting block on the base plate m^0 and projects through a slot in the rear of the magazine, close to the locking lever n^0 . The lower end of this locking lever n^0 has an engaging surface which is so shaped that it is able to pass over the lower edge of the stock when the lever is pushed into and out of position. The locking lever n^0 is held in position in the stock by a special holding arm i' , which, by means of a lateral spring piece i' , also holds the locking lever in engagement. The construction of the magazine holder explains its action; in Fig. 4 the same is shown in engagement in which its shoulder engages underneath the projection m^4 and thus holds the magazine in position. When it is desired to take out the magazine the lever n^0 must be pushed sidewise in order to release the projection m^4 , whereupon the magazine can be pulled out.

125

What I claim as my invention, and desire to secure by patent is:

1. In a magazine for fire arms, the combination of a cartridge elevator having a catch or pawl adapted to engage the magazine to prevent the cartridges from being tipped over backward in the magazine.

2. In a magazine for recoil loading fire arms having a cartridge elevator, a spring operated arresting pawl for said elevator, and

130

co-acting slots formed in the wall of the magazine for engaging said pawl to prevent the cartridges from being tipped backward by the action of the recoil.

5 3. A magazine for fire arms having a cartridge elevator, a catch or pawl for said cartridge elevator adapted to prevent the cartridges from tipping backward, and means for disengaging said catch when the magazine is to be filled.

10 4. A magazine for recoil loading fire arms having a cartridge elevator, a spring catch or pawl for said elevator, co-acting slots in the wall of the magazine adapted to engage said catch, and a plate having means for filling said slots to permit the catch to move past them when the magazine is to be filled.

15 5. In a fire arm the combination of a magazine adapted to be connected to the body of the fire arm, and a magazine locking lever pivoted to said fire arm and adapted to engage

20 said magazine, said lever being adapted to turn upon its pivot in a direction transverse to the longitudinal direction of the weapon to release said magazine.

25 6. The combination of a fire arm having a magazine stock, of a magazine adapted to fit within said stock, and a magazine locking lever pivoted to the rear wall of said stock and adapted to engage a shoulder formed on the magazine, said locking lever being adapted to turn on its pivot in a direction transverse to the longitudinal direction of the weapon to release said magazine.

30 In witness whereof, I have hereunto signed my name in the presence of two subscribing witnesses.

PAUL MAUSER.
